UNITED STATES PATENT OFFICE

WILLIAM A. TOLSON, OF REXFORD, NEW YORK, ASSIGNOR TO GENERAL ELECTRIC COMPANY, A CORPORATION OF NEW YORK

SIGNAL SYSTEM

Application filed March 17, 1928. Serial No. 262,581.

My invention relates to signal systems and more particularly to certain improvements in the control circuits for such systems.

Still more particularly my invention relates to signaling systems in which electron discharge devices are employed as amplifiers, oscillation generators or the like, and in which it is desired to operate certain control circuits, relays and the like in response to the anode current flowing therein.

In high frequency signal systems by means of which duplex communication is affected with carrier currents of a single frequency it is usual to employ normally inoperative oscillation generators which are controlled automatically in response to application of signal currents to the transmitting apparatus. Means for effecting this automatic control are shown and described in Patent No. 1,696,566 of Emmett F. Carter, issued December 25,

1928, entitled High frequency duplex signaling system which is assigned to the same assignee as the present application. It is likewise customary in systems of this kind to provide means for protecting the receiving equipment against potentials which are induced in it during periods when the transmitting equipment is operating. Improved means for this purpose in which an electron discharge device connected in shunt with the receiving circuit is controlled by the anode current flowing in an automatically controlled oscillation generator are disclosed in Patent No. 1,696,593, Emmett F. Carter, issued December 25, 1928, entitled High frequency signaling system which is also assigned to the same assignee as the present application.

In certain types of signal systems, such, for example, as in carrier current repeating systems, it has been found that the protection which is applied to one channel in response to application of signal currents to the other channel should be very complete. In these systems an automatically controlled oscillation generator is employed for transmission in each direction and each of these generators is controlled in response to signal currents which flow from a detector of a received carrier wave. The input to each detector is in-

ductively associated with the output from the transmitter which is employed for transmission in the opposite direction and in consequence a complete singing circuit exists through the two channels thus mutually connected together. If currents from one transmitter reach the opposite detector the other transmitter will be caused to operate which in turn will supply currents to the detector associated with the first transmitter and the above-mentioned singing will result. Such will be the case even though the amount of energy which reaches the two detectors is very small. Thus the protection which is applied to each channel must be very complete such as that which is afforded by a mechanical relay having contacts which are arranged to open circuit, or short circuit, or both, either of the channels in response to operation of the opposite channel.

In the use of mechanical relays difficulties are encountered resulting from the time delay incident to the actuation of the armatures thereof. Accordingly one of the purposes of my invention is to so arrange a mechanical relay in the circuit such that it may be operated in response to signal currents without producing undesirable effects resulting from the time delay incident to the operation of its armature.

A further purpose of my invention is to provide means whereby a signal circuit may be automatically controlled by means of a mechanical relay in response to operation of an electron discharge device such as an amplifier or oscillation generator without detrimentally affecting the operation of those devices.

The novel features which I believe to be characteristic of my invention will be set forth with particularity in the appended claims. My invention itself, however, both as to its organization and method of operation, may best be understood by reference to the following description taken in connection with the accompanying drawing in which Fig. 1 shows one form of my invention as applied to a carrier current repeating circuit and in which Fig. 2 represents a modification thereof,

Referring to Fig. 1 of the drawing, in which I have shown as much of the equipment as is necessary to an understanding of my invention, 1 represents the apparatus which is operated during transmission in one direction and 2 represents the apparatus which is operated during transmission in the opposite direction. These channels, 1 and 2, are interconnected in the usual manner by means of hybrid coils 3 and 4. These hybrid coils are connected through circuits 5 and 6 respectively to suitable antenna systems or to wire line circuits such, for example, as those of the usual power distribution system. These hybrid coils are also provided, in the usual manner, with balancing networks 7 and 8 respectively.

In the channel 1 is employed an electron discharge oscillation generator 9, between the anode and grid of which is connected the usual oscillatory circuit 10. High frequency currents are supplied from this oscillation generator through the coupling condenser 11, suitable amplification and modulation apparatus 12, and conductors 13 to the hybrid coil 3, from which they are communicated to the transmission media through the circuit 5. The oscillation generator 9 is adapted to be controlled in response to received signals by means of an electron discharge device 14. This device is of the usual three element type and has the space between its anode and cathode connected in circuit with the discharge path of the oscillation generator 9. This circuit may be traced from the negative side of the source of potential 15 through conductor 16, resistance 17, space between the cathode and anode of the discharge device 14, space between the cathode and anode of the discharge device 9 and choke coil 18 to the positive side of the source of potential 15. Normally the impedance of the discharge device 14 is such that substantially no current flows in this circuit and hence the electron discharge device 9 is normally inoperative. This impedance may be obtained by supplying suitable biasing potential to the grid of device 14. When high frequency currents are received from the circuit 6 they are detected by the device 19 and the signal currents therefrom are impressed upon the grid of the control device 14. The impedance between the anode and cathode of this device is then sufficiently diminished to permit current to flow through the anode circuit of the oscillation generator 9, and hence this device is rendered operative. High frequency currents are then supplied by the oscillation generator 9 to the apparatus 12, where they are modulated by signal currents which are supplied thereto through the conductors 20. These modulated high frequency currents are then supplied to the transmission media through the hybrid coil 3 and circuit 5.

Channel 2 which is adapted for communi-

cation in the opposite direction is identical with the channel 1 and hence its circuit construction will not be more fully explained. When high frequency currents are received from the circuit 5 they are impressed upon the grid of the detector 21 where the voice, or signal, currents are detected. These voice, or signal, currents are then supplied through the transformer 22 to the transmitting apparatus 23 where they are impressed upon the grid of a control device corresponding to the device 14 of the channel 1 and also upon suitable modulation apparatus. High frequency currents produced by the oscillation generator, which is included in the apparatus 23, are then communicated through the hybrid coil 4 and circuit 6 to the transmission media.

As thus constructed it will be seen that, during operative periods of the oscillation generator 9, if currents from this device reach the detector 21 and the control device associated with the transmitting equipment 23, high frequency currents will be supplied through the hybrid coil 4, both to the line 6 and to the channel 1. This is particularly true in view of the difficulties encountered in balancing these hybrid coils to currents having the frequency of the carrier wave. These currents will then in turn cause the operation of oscillation generator 9 which will continue to supply currents through the hybrid coil 3. Thus singing of the circuit will result. To prevent this a relay 24 having a pair of normally closed contacts 29 and 30 and a pair of normally open contacts 29 and 31 is provided, such that when this relay is energized the input to the transmitting device 23 is open circuited by the contacts 29 and 30 and the output from the detector 21 is short circuited by the contacts 29 and 31. Thus no transmission of energy through this channel can take place. In accordance with my invention means are provided whereby this relay may be caused to quickly respond to the direct current flowing in the anode circuit of the oscillation generator 9.

In common with circuits in which reactance is included the current in the anode circuit of the oscillation generator 9, after voice currents have been applied to the grid of the control device 14, builds up in accordance with an exponential characteristic. After the current in this circuit has built up to a certain value oscillations will be produced by the device 9. To produce quick response of a pair of contacts, such as those of the relay 24, to application of signal currents to the transmitter by means of this current it is necessary that the relay should operate before the current reaches its normal value and preferably while it is at a small fractional part of its normal value. Were the actuating coil of the relay connected directly to the anode circuit of the device 9 and operated directly in response to a small fraction of this current

it will be seen that a very sensitive relay and one having high resistance would necessarily be employed. Unless additional means are employed a high voltage will be produced across the relay when normal current flows in the oscillation generator and this high voltage will so diminish the potential between the anode and cathode of the oscillation generator 9 as to impair its operation. To overcome this difficulty I have provided special means such as are shown in Figs. 1 and 2.

In accordance with the form shown in Fig. 1 I have included in the anode circuit of the oscillation generator 9 an impedance 17 as above-mentioned. In parallel with this impedance is connected the space between the grid and cathode of an electron discharge device 25 in the anode circuit of which is included the relay 24 and an additional relay 26, the purpose of the latter of which will later be set forth. A source of biasing potential 27 is used to normally impress a negative potential upon the grid of the discharge device 25 such that when no current flows through the resistance 17, the space between the grid and cathode of the device 25 represents a very large impedance. The effect of this potential is also to preclude the flow of anode current through the discharge device 25 and hence through the actuating windings of the relays 24 and 26. When current is caused to flow in the resistance 17, however, as due to signal currents being applied to the grid of the device 14 this biasing potential will be overcome and current will be caused to flow through the relays 24 and 26 having sufficient magnitude to cause the operation of the device 24 when the anode current of the oscillation generator 9 is still at a very small value. As this current increases the impedance between the grid and cathode of the device 25 is diminished and hence when the anode current of the device 9 reaches its normal value a very substantial portion thereof, which may be 60% or greater will flow through the space between the cathode and grid of the device 25 rather than through the resistance 17. Thus after the device 24 is operated the impedance across the terminals of the resistance 17 is increasingly diminished and hence the potential appearing across the resistance 17 does not become of magnitude such that it impairs the operation of the oscillation generator 9. In this manner a very rapid response of the relay 24 can be produced in response to application of the signal currents to the transmitting circuit. In fact it has been found that the relay 24 can be caused to operate before the initiation of high frequency currents by the generator 9.

The oscillation generator 9 is provided with the usual grid leak resistance 28. This resistance is adapted to be normally short circuited by means of the contacts of relay 26.

Relay 26 is so adjusted that its contacts do not separate until the current in the anode circuit of the oscillation generator 9 has built up to a certain desired value. In this way operation of the oscillation generator 9 in response to noises which may normally exist in the operating room may be prevented.

In a manner similar to that above described when currents are received from the line 5 and are detected by the device 21 and supplied to the transmitter equipment 23, protection will be applied to the channel 1 through conductors 32 which lead to a relay corresponding to the relay 24 which is included in the receiving apparatus 19.

Referring to Fig. 2, I have shown a modification of my invention in which the relay 24 is connected directly in circuit with the cathode and anode of the control device 14 and oscillation generator 9 not shown. This relay is of high resistance and is adapted to operate in response to a small fraction of the normal anode current. In parallel with the relay 24 is connected a two electrode discharge device 25' which is provided with a source of biasing potential 27. As thus arranged, as the current through the relay 24 increases the relay will be caused to operate and the potential appearing thereon will overcome the biasing potential of the device 25'. The impedance of this device will then become greatly diminished and when the anode current of device 14 approaches its normal value a substantial portion of it will flow through the device 25'. In this way the building up of a large potential upon the relay 24 is prevented.

While I have described my means for producing a rapid response of a relay such as relay 24 with particular reference to signal systems and to its application to the control circuits of such systems and also with particular reference to the controlling of relay contacts in response to the anode current flowing in an oscillation generator, it will, of course, be understood that I do not wish to be limited thereto since my system may be employed in any case where it is desired to operate a relay in response to current flowing in an operating circuit without seriously affecting the operation of the circuit itself as by causing a large potential to appear across the relay.

Likewise while I have shown and described a single embodiment of my invention it will, of course, be understood that I do not wish to be limited thereto since many modifications, both in the circuit arrangement, and in the instrumentalities employed, may be made without departing from the spirit and scope of my invention as set forth in the appended claims.

What I claim as new and desire to secure by Letters Patent of the United States is:

1. In combination, a circuit, a pair of contacts, means for operating said contacts in response to current flowing in said circuit without substantially changing the characteristics of the circuit to normal flow of current therein, said means including an impedance connected in said circuit and means for causing operation of said contacts in response to the potential on said impedance when the current flowing therein is equal to a fractional part of the normal current and for producing a shunt around said impedance for currents of value greater than said fractional part, said shunt having impedance such that under normal operating conditions of said circuit a substantial portion of the current in said circuit flows through said shunt.

2. In combination, an electron discharge device having an anode circuit, means for controlling said anode circuit thereby to control the operation of said discharge device, a pair of contacts, an impedance connected in said anode circuit and means for operating said contacts in response to potential on said impedance when the current flowing therein is a fractional part of the normal value and for producing a shunt around said impedance for currents greater than said fractional part, said shunt having impedance such that under normal operating conditions of said electron discharge device a substantial portion of the current in said circuit flows through said shunt whereby said contacts are operated without materially affecting the normal operation of said discharge device.

3. In a signaling system, a receiving circuit, a transmitting circuit including a normally inoperative electron discharge device having an anode circuit, means for rendering said device operative in response to application of signal currents to said transmitter, a pair of contacts for controlling said receiving circuit, an impedance connected in said anode circuit and means for operating said contacts in response to the potential on said impedance when the current therein is a fractional part of the normal value and for producing a shunt around said impedance for currents greater than said fractional part.

5. In a signaling system, a receiving circuit, a transmitting circuit including a normally inoperative electron discharge device having an anode circuit, means for rendering said device operative in response to application of signal currents to said transmitter, a pair of contacts for controlling said receiving circuit, an impedance connected in said anode circuit, means for operating said contacts in response to the potential on said impedance when the current therein is a fractional part of the normal value and an electron discharge device connected in shunt with said impedance having high resistance for values of current in said impedance smaller than said fractional part and low resistance

for values of current greater than said fractional part.

5. In combination, an electron discharge oscillation generator having an anode circuit, a relay, means for operating said relay in response to rise in current in said anode circuit, said means comprising an impedance connected in said anode circuit, an electron discharge device having grid and anode circuits, said relay being connected in said last anode circuit and said impedance being included in said grid circuit whereby when the current in said impedance rises said relay is caused to operate and the impedance of said device is reduced sufficiently to permit a substantial portion of said anode current to flow through said grid circuit.

6. In combination, an electron discharge oscillation generator having an anode circuit, a relay, means for operating said relay in response to rise in current in said anode circuit, said means comprising an impedance connected in said anode circuit, an electron discharge device having grid and anode circuits, said relay being connected in said last anode circuit and said impedance being included in said grid circuit whereby when the current in said impedance rises said relay is caused to operate and the impedance of said device is reduced sufficiently to permit a substantial portion of said anode current to flow through said grid circuit and additional means responsive to said rise in current for controlling said oscillation generator.

7. In a signal system, a receiving circuit, a transmitting circuit including an electron discharge oscillation generator having an anode circuit, means for controlling said oscillation generator, means for controlling said receiving circuit in response to operation of said oscillation generator, said means comprising a resistance connected in said anode circuit, an electron discharge device having an anode, a cathode and a grid, said cathode and grid being connected in shunt with said resistance, means for biasing the grid of said device such that the impedance between said grid and cathode is high when no current flows in said resistance and becomes comparatively low when the current in said resistance approaches normal value, and a relay connected between said anode and cathode for controlling said receiving circuit.

In witness whereof, I have hereunto set my hand this 16th day of March, 1928.

WILLIAM A. TOLSON.
